UNITED STATES PATENT OFFICE

EDWARD C. RASSEL, OF MIO, MICHIGAN

RAILROAD TIE

Application filed April 5, 1930. Serial No. 441,943.

The present invention relates to a railroad tie and has for its prime object to provide a metallic tie which is simple in construction, comparatively inexpensive to manufacture, 5 strong and durable and efficient and reliable in use.

Another very important object of the invention resides in the provision of a tie which is provided with means whereby the rails may 10 be effectively locked thereto in an easy and expeditious manner without the use of spikes and other separable fastening means.

Referring to the drawing in detail it will be seen that Figure 1 is a top plan view of the tie embodying the features of my invention,

Figure 2 is a side elevation thereof,

Figure 3 is a longitudinal section therethrough,

Figure 4 is an enlarged detail sectional view taken substantially on the line 4—4 of Figure 1,

Figure 5 is a fragmentary top plan view of another embodiment of the invention,

Figure 6 is a transverse section therethrough taken substantially on the line 6—6 of Figure 5,

Figure 7 is a fragmentary longitudinal section taken substantially on the line 7—7 of Figure 5, and

Figure 8 is a perspective view of one of the cushioning blocks.

Referring to the drawing in detail and first to the embodiments illustrated in Figures 1 to 4 inclusive it will be seen that the tie comprises an elongated inverted channel shaped metallic casting comprising a top plate 5 with longitudinal depending sides 6 with bracing webs 7 therebetween and the sides 6 having outwardly directed foot flanges 8. In the plate 5 at the end portions thereof are formed recesses 9 to receive the feet of the rails and rising from the plate 5 immediate the sides of the recesses are bendable clips or tongues 10 which may be bent over the top portions of the feet of the rails to hold them down in the recesses or seats.

These clips, of course, take the place of the usual spike now in use. In Figures 5 to 8 I have shown another embodiment of the in-

vention wherein an elongated channel shaped body includes a top plate 5', sides 6' and flanges 8'.

Openings are provided in the top plate from which depend downwardly converging webs 12 formed with shoulders 14 at their upper ends. Downwardly tapering cushion blocks 15 of wood or similar material are inserted between the webs 12 and the rail is adapted to sit thereon, the shoulders 14 limiting the downward movement of the rail.

Clips 10' similar to clips 10 are also used in this embodiment. It is thought that the construction, utility and advantages of this invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention what I claim as new is:

1. A railroad tie of the class described comprising an elongated channel-shaped body open at the bottom comprising an elongated substantially rectangular top plate, and substantially rectangular side plates depending rightangularly from and extending completely the length of the longitudinal edges of the top plate, said top plate being provided with a pair of inset portions, forming shoulders for seating a rail, a bendable rectangular tongue rising from the top plate adjacent one shoulder, and another bendable rectangular tongue rising adjacent the opposite shoulder of each inset portion, said tongues being diagonally opposed near opposite longitudinal edges of the top plate and adapted to be bent upon the feet of a pair of rails seated in said inset portions, and webs

supporting the central under portions of said insets, and formed transversely of each tie and between and attached to said top plate and said sides.

5 2. A railroad tie of the class described comprising an elongated channel shaped body open at the bottom comprising an elongated substantially rectangular top plate, and substantially rectangular side plates depending rightangularly from and extending completely the length of the longitudinal edges of the top plate, said top plate provided with a pair of inset portions forming shoulders for seating a rail, and a bendable rectangular tongue rising from the top plate adjacent one shoulder, and another bendable tongue similarly rising adjacent the opposite shoulder of each inset portion, said tongues being diagonally opposed near opposite longitudinal edges of the top plate and adapted to be bent upon the feet of a pair of rails, seated one in each inset portion, and said inset portions being cut away inwardly of said shoulders to define mouths of open bottomed wells, said wells formed by the sides of the ties, and a pair of downwardly and inwardly inclined transverse webs constructed between said walls and extended from the top plate to the bottom of the side plates and having their inner faces flush with the mouths of said wells, and a frusto-pyramidal cushion block inserted in each of said wells, adapted to be engaged by the bottoms of the rails and the portion of the inset portions between the two shoulders and the mouths of the wells constituting stops for preventing downward displacement of the rails.

40 3. A railroad tie of the class described comprising an elongated channel-shaped body open at the bottom comprising an elongated substantially rectangular top plate, and substantially rectangular side plates depending rightangularly from and extending completely the length of the longitudinal edges of the top plate, said top plate being provided with a pair of inset portions forming shoulders for seating a rail, a bendable rectangular tongue rising from the top plate adjacent one shoulder, and another bendable rectangular tongue rising adjacent the opposite shoulder of each inset portion, said tongues being diagonally opposed near opposite longitudinal edges of the top plate and adapted to be bent upon the feet of a pair of rails seated in said inset portions, and webs formed transversely of the tie and between and attached to said top plate and said sides and supporting said inset portions.

In testimony whereof I affix my signature.
EDWARD C. RASSEL.
